UNITED STATES PATENT OFFICE

2,427,720

KNITTING MACHINE

Oscar Fregeolle, Central Falls, R. I., assignor to
Hemphill Company, Central Falls, R. I., a corporation of Massachusetts

Application February 27, 1945, Serial No. 579,915

16 Claims. (Cl. 66—43)

1

This invention relates to a new and useful improvement in knitting machines of the circular, independent needle, type and particularly to machines adapted to carry out the method of knitting described in U. S. Patent #2,360,668 in which at least one yarn is drawn over the backs of sinkers behind the nibs instead of in their throats during rotary or reciprocatory knitting or both. The invention relates primarily to an improved sinker cam cap for knitting by the method mentioned above and particularly for plating a reciprocatorily knit instep. The invention also includes means for insuring that the knitted instep loops will be positioned at throat level at the beginning of the heel and toe, also means which insures that no sinker throat or nib will engage the instep yarn during the reciprocatory knitting of the heel or toe and means for retarding the beginning of the downward knitting motion of the needles with respect to the inward projection of the sinkers.

One form of the invention as applied to a Banner type machine is described herein and illustrated in the drawing of which:

Fig. 1 is a plan view of the sinker cam cap;

Fig. 2 is a side elevation of the same sinker cam cap;

Fig. 3 is a plan view of a part of a sinker cam cap and sinkers and also showing diagrammatically the needle circle and auxiliary yarn feed;

Fig. 4 is a view of needles and sinkers to aid in explaining the operation of the sinkers by certain of the cams shown in Fig. 3;

Figs. 5 and 6 are sections through the sinker cam cap of Fig. 3 along the lines 5—5 and 6—6, respectively, and also showing a sinker and a needle;

Fig. 7 is a view of the needle operating cams at the auxiliary side of the machine;

Fig. 8 is a sectional view along the line 8—8 and of Fig. 7;

Figs. 9 and 10 are diagrammatic views of a sinker and needle illustrating the effect produced by certain of the cams in Fig. 7; and

Figs. 11 and 12 are developed views showing diagrammatically the paths followed by the needles to fulfill various knitting conditions.

The machine which will be described is provided with the usual rotatable cylinder carrying the usual complement of long and short butt needles constituting the instep and sole groups and with means for transferring any desired number of the short butt sole needles to the long butt group whenever a smaller heel or narrow sole and a correspondingly wider instep are de-

sired. The machine also has the usual main and auxiliary cam blocks and knitting cams.

The sinker cam cap 1 of this invention is shown in Figs. 1 and 2. Unlike the ordinary sinker cap it does not swing to position the sinker cams for knitting in each direction. Instead it is held in a fixed position by adjusting screws 2 and 3 adapted to make contact with opposite sides of a suitable fixed abutment 4. By means of screws 2 and 3 the cap can also be very accurately adjusted with respect to the needle cams. This sinker cam cap is suitable for rotary or reciprocatory knitting of the usual kinds but is particularly good for plating a reciprocatorily knit instep at the auxiliary side by the method described in copending application #549,157, filed August 12, 1944, now Patent No. 2,402,744, in which both the body and plating yarns are drawn over the backs of the sinkers behind their nibs.

As will be seen from Fig. 1 the center sinker cam 5 on the auxiliary side is made as short as possible. This permits the sinkers to be moved in by cam 6 or 7 depending upon the direction of knitting immediately after they have been drawn out for transferring loops from their backs to their throats so as to be placed as soon as possible in the proper position to receive the body and plating yarns over their backs. These yarns may be fed by a feed such as that diagrammatically illustrated at 8 in Figs. 11 and 12 positioned below the carrier ring so that the feeding angle is unusually low. It is necessary, therefore, to bring the sinkers in as far ahead of the knitting point as possible to insure that the nibs of all of them will pass beneath both yarns. Since the sinkers must be out when the needles pass under the point of the center guard cam of the auxiliary knitting cams the top of said center sinker cam would necessarily have the familiar long flat shape if the sinker cam cap were permitted to swing in the customary manner. Because this sinker cam cap is fixed the extremely short center cam 5 is adequate since it can be positioned directly above the center guard cam referred to.

A fixed sinker cam cap also makes it possible to position the other sinker cams, such as casting off cams 9 and 10, symmetrically. This also applies to the sinker cams on the main side of the machine including center cam 11 and casting off cams 12 and 13.

The sinker cam cap shown in Fig. 1 is also provided on the main side with two opposed, pivoted flopper cams 14 and 15. These also are symmetrically positioned with respect to center cam 11. Flopper cam 14 is shown in its outward, in-

operative position and flopper cam 15 is shown in its inward, operative position. These are the positions assumed by these cams for counter-clockwise knitting at the main, auxiliary or both stitch cams. The purpose of the flopper cam 15 is to hold the sinkers in to prevent the fabric from being carried up by the needle shanks when they move up the front stitch cam 16 of the main cam block, see Fig. 11. When knitting in clockwise direction the positions of flopper cams 14 and 15 are reversed, flopper cam 14 being in and flopper cam 15 out. When in these positions flopper cam 14 serves to hold the sinkers in while the needles are moving up the rear stitch cam 17. Since flopper cam 15 in its inoperative position corresponding to that shown for flopper cam 14 in Fig. 1, the usual casting off cam 13 can operate in the usual way.

Nothing of this sort is required at the auxiliary side since the instep needles are raised while the sinkers are in and thereafter follow an intermittently descending path to the stitch cam under which they knit, i. e., cam 18 or 19 depending upon the direction of knitting. The path followed by the instep needles in clockwise knitting is shown at 20 in Fig. 11. The reverse path is not shown but is similar and will be clear to those skilled in the art.

Although flopper cam 15 is operating while counter-clockwise knitting is in progress at the auxiliary stitch cam only, it serves no essential purpose since the needles which are knitting do not go over the front stitch cam 16 of the main cam block as will be seen from Fig. 12 in which the path followed by the needle butts during counter-clockwise rotary knitting is shown at 21. However, it does no harm and is in condition to operate when needed to assist when knitting is being done at the main stitch cams.

Flopper cams 14 and 15 and casting off cams 12 and 13 are each about half as thick as usual so that the combined vertical thickness of each pair is equal to the thickness of an ordinary sinker cam. Flopper cam 14 is mounted above casting off cam 12 and flopper cam 15 under casting off cam 13.

When knitting the heel and toe the leg or instep yarn, which is fed and knitted on the auxiliary side of the machine, is idle. As is well known, the throw of the needle cylinder with reference to the auxiliary yarn feed is much greater in the clockwise direction than in the other. For example, as shown in Fig. 3, at the end of a clockwise knitting stroke the instep yarn 23, extending from yarn feed 8 to the instep needle 22 which was the last to knit before reciprocating knitting was begun, stretches more than half way around the needle circle whereas in counter-clockwise knitting the instep yarn cuts directly across a much smaller arc of the needle circle as indicated at 23'.

The distance between needle 22 and yarn feed 8 at the end of a clockwise stroke results in a very small angle of slope for instep yarn 23. Therefore, if towards the end of such a clockwise stroke the sinkers adjacent to and following needle 22 were moved in in the usual way, those nearest to needle 22 would probably take yarn 23 in their throats but those a little further away would almost certainly damage or cut it through contact with the nibs as indicated in Fig. 4. Also during counter-clockwise knitting a sawing effect upon the yarn would be caused by these sinkers for the same reason.

To avoid this, the sinkers associated with the

instep needles immediately following needle 22, assumed for the purpose of this application to be the eight sinkers 24 to the right instep needle 22 (Fig. 3), are provided with short butts such as 5 that shown at 25 in Fig. 5. The height of these butts is such that they can be engaged only by the two lowest cams of the pairs 12, 14, and 13, 15, specifically fixed cam 12 and flopper cam 15. The other sinkers have long butts 26 as shown in 10 Fig. 6 so that they are engagable by either cam of both of these pairs when in operating position. Consequently, since during clockwise knitting flopper cam 15 is out of action as heretofore described, the sinkers of group 24 will pass under cam 13 and will not be moved in or otherwise affected by it or by cam 15.

Therefore, these sinkers cannot possibly cut or injure the instep yarn 23. It is assumed that the 20 yarn will be above the nibs of the sinkers following group 24 so that the remaining sinkers associated with the long butt instep needles can be projected in the usual way by cam 13 without interfering with yarn 23. Therefore, as already 25 stated, these sinkers are provided with butts 26 of a length adequate to be engaged by any one of the cams 12, 14, 13 and 15. Of course, the number of short butt sinkers corresponding to group 24 is not necessarily eight but may be the number required to accomplish the described result.

30 Flopper cams 14 and 15 are operated by means of a ring 27 (Figs. 1, 2 and 7) frictionally mounted on the sinker head 28 so that it will rotate with it as far as permitted. Such rotation is limited by screws 29 and 30 in lugs 31 and 32 projecting 35 from ring 27. A fixed abutment 33, shown here as a tubular member of the machine frame, limits the tendency of ring 27 to rotate within the space between screws 29 and 30. These screws also serve as adjustments for determining the exact extent through which ring 27 can swing.

Projecting upwardly from ring 27 are two fingers 34 and 35 so positioned that finger 34 will engage the outer edge of flopper cam 14 to swing the cam to its inward, operating position when a clockwise stroke is begun and finger 35 will do likewise with flopper cam 15 for counter-clockwise strokes. However, as it will be seen from Figs. 1 and 2, the inward swing of each of these 45 flopper cams is somewhat delayed because a considerable movement of fingers 34 and 35 is required to operate them. As a result of this, the sinkers constituting group 24 will remain out long enough so that the difficulty already described is avoided. Flopper cams 14 and 15 are 50 swung out when released by fingers 34 and 35, respectively, by leaf springs 36 and 37 acting upon pins 38 and 39 projecting downwardly from the flopper cams.

As already stated, the center sinker cam on the auxiliary side is positioned directly above the center guard cam of the knitting cams. Because of this another novel feature, which is also a part of this invention, is possible.

60 In Fig. 7 the rear and front auxiliary knitting cams are indicated at 19 and 18, respectively. The center guard cam 40 between them is mounted on a horizontal pivot 41 in a bracket 42 (Fig. 8) so that it can swing to the left or right corresponding to the direction in which knitting is being done. The face of this cam opposite the needle cylinder is recessed as indicated at 43 so that when in 65 operating position, during reciprocating knitting, it envelops fixed center cam 44 so that this cam 70 44 is inoperative. When cam 40 is retracted to

75 44 is inoperative. When cam 40 is retracted to

its inoperative position as shown in Fig. 8, center cam 44 is uncovered and able to operate.

By pivoting cam 40 so that it swings as above described the point at which the needles begin to descend in either direction of knitting is retarded. This is particularly useful when wrap patterns are being made since it provides more time for bringing the eyelet, finger or other yarn feeding part of the wrapping mechanism back to the inside of the needle circle and also because it provides more time and space for the moving of the sinkers immediately after they have passed center sinker cam 5 so that their backs will be presented to the yarn. This will be made evident by Figs. 11 and 12. The variation from the regular needle paths when wrapping is indicated at 45 and 46 in these respective figures.

As will be understood by those skilled in the art and from U. S. patent referred to above, the last stroke of counter-clockwise knitting is completed before the machine reverses to begin the knitting of the heel or toe the instep yarn will have been drawn over the backs of the sinkers by the instep needles. A few of these needles will have passed by center sinker cam 11 at the main side of the machine and the corresponding sinkers will have been drawn out so that the loops have been transferred from their backs over their nibs to their throats. The remaining instep needles have not reached the point of the needle circle corresponding to sinker cam 11 so that the corresponding sinkers will not have been drawn out by that cam. Therefore, these sinkers remain in and the newly drawn instep loops remain on their backs. This condition persists during the following clockwise stroke until these needles and their associated sinkers reach center sinker cam 5 at the auxiliary side of the machine by which the sinkers are drawn out to transfer the loops on their backs to their throats.

Because sinker cam 5 is extremely short, the sinkers are moved in again immediately by either cam 6 or cam 7 and there may not be time for the transferred loops to work down the shanks of the needles to throat level. Therefore, these loops may remain above the nibs of the associated sinkers or may slip down only enough to be struck by the nibs when they advance. To insure that these loops are definitely positioned at throat level before they can be interfered with or damaged by the sinker nibs, the needles are caused to lower the adjacent sinker loops sufficiently, while the sinkers are being pulled out by center cam 5, to insure that the sinker loops will be at throat level when the sinkers are again moved in.

Before the knitting of the heel or toe is begun center guard cam 40 is pulled out into its inactive position shown in Fig. 8. This, as already explained and as shown in that figure, uncovers fixed center guard cam 44 and permits it to act upon the needle butts. The point 41 of center cam 44 is lower than the points of adjacent guard cams 48 and 49 so that the needles, after they pass under one or the other of these cams, will receive an additional limited downward movement by center cam 44. This will carry the loops referred to to the level of the sinker throats. The point of center guard cam 44 is in the same plane radially of the needle cylinder as the point of center sinker cam 5. Therefore, the withdrawing of sinkers and the drawing down of the needles occur simultaneously so that, when the sinkers are all the way out and their nibs wholly outside of the needle shanks the loops will be all the way down. In this way, the sinker loops

referred to are protected from damage at this time and properly positioned for subsequent casting off when knitting at the auxiliary side is resumed.

5 The above is illustrated diagrammatically by Figs. 9 and 10. In Fig. 9 the sinker 50 has been pulled out and the sinker loop 51 transferred from its back over its nib. However, unless, the needle 52 is moved down the needle loop 53 and, 10 consequently, the adjacent sinker loops 51 are likely to remain at the transfer height as indicated at which they are not properly positioned either for safety or for casting off. In Fig. 10 the needle is assumed to have been moved down by center guard cam 44 as above described. It will be seen that the needle and sinker loop have moved with it and that the sinker loop is now resting at its proper height on the throat of the sinker.

20 20 After the loops referred to have been lowered in this way during the first reverse stroke of the machine at the beginning of the heel or toe they are not likely to rise again because the sinkers remain in practically continuously. However, 25 center cam 44 continues to function as above described throughout the knitting of the heel and toe and thereby insures that the loops remain properly positioned in case of some irregularity in the action of the machine or of the fabric.

30 30 That the sinker cam cap of this invention is peculiarly adapted for plating at the auxiliary knitting cams by the method in which the body and plating yarns are both drawn over the backs of the sinkers behind the nibs has already been 35 mentioned. This is indicated in Figs. 11 and 12 the body yarn being shown at 23 and the plating yarn at 54 in these figures. Incidentally, the wrap yarn 55 is also shown in these figures and the deviation from the normal path taken by the 40 needles selected for wrapping. As shown, the method of wrapping just described is limited to the knitting at the auxiliary knitting cams, any plating at the main side being done in the usual way in the throats of the sinkers.

45 I claim:

1. In a knitting machine provided with main and auxiliary knitting cams, a fixed sinker cam cap having on the auxiliary side a center sinker cam for drawing out sinkers which consist of 50 two sides converging substantially to a point, a center sinker cam at the main side, two fixed casting off cams symmetrically positioned on opposite sides of said main center sinker cam and two flopper cams also symmetrically positioned 55 on opposite sides of said center sinker cam, one of said flopper cams being below the corresponding casting off cam and the other above its corresponding casting off cam.

2. In a knitting machine having main and auxiliary knitting cams and adapted to draw one or more yarns over the backs of sinkers to knit at said auxiliary knitting cams a fixed, sinker cam cap having a center sinker cam at the main side, two fixed casting off cams symmetrically 60 positioned on opposite sides of said main center sinker cam and two flopper cams also symmetrically positioned on opposite sides of said center sinker cam, one of said flopper cams being below the corresponding casting off cam and the other above its corresponding casting off cam.

65 3. In a knitting machine having main and auxiliary knitting cams and adapted to draw one or more yarns over the backs of sinkers to knit at said auxiliary cams, a fixed sinker cam cap having on the auxiliary side a center sinker cam 70

75 having on the auxiliary side a center sinker cam

for drawing out sinkers which consist of two similar sides converging substantially to a point, a center sinker cam at the main side, two fixed casting off cams symmetrically positioned on opposite sides of said main center sinker cam and two flopper cams also symmetrically positioned on opposite sides of said cam, center sinker cam, one of said flopper cams being below the corresponding casting off cam and the other above its corresponding casting off cam, a complement of needles divided into instep and sole groups, a corresponding number of sinkers all having butts of the same length with the exception of the first few sinkers associated with the instep group of needles preceding the last instep needle to knit prior to the first course of the heel or toe, said few sinkers having shorter butts which are long enough to engage the lower casting off and flopper cams but are too short to engage the upper casting off and flopper cams.

4. In a knitting machine having main and auxiliary knitting cams and adapted to draw one or more yarns over the backs of sinkers to knit at said auxiliary cams, a fixed sinker cam cap having off cams symmetrically positioned on opposite drawing out sinkers which consist of two similar sides converging substantially to a point, a center sinker cam at the main side, two fixed casting off cams symmetrically positioned on opposite sides of said main center sinker cam and two flopper cams also symmetrically positioned on opposite sides of said cam, center sinker cam, one of said flopper cams being below the corresponding casting off cam and the other above its corresponding casting off cam, a complement of needles divided into instep and sole groups, a corresponding number of sinkers all having butts of the same length with the exception of the first few sinkers associated with the instep group of needles adjacent the last instep needle to knit prior to the first course of the heel or toe, said few sinkers having shorter butts which are long enough to engage the lower casting off and flopper cams but are too short to engage the upper casting off and flopper cams.

5. In a knitting machine having main and auxiliary knitting cams and adapted to draw one or more yarns over the backs of sinkers to knit at said auxiliary cams, a fixed sinker cam cap having on the auxiliary side a center sinker cam for drawing out sinkers which consist of two similar sides converging substantially to a point, a center sinker cam at the main side, two fixed casting off cams symmetrically positioned on opposite sides of said main center sinker cam and two flopper cams also symmetrically positioned on opposite sides of said cam, center sinker cam, one of said flopper cams being below the corresponding casting off cam and the other above its corresponding casting off cam, a cylinder having a complement of needles divided into instep and sole groups the instep group including at times some needles of the sole group, a corresponding number of sinkers all having butts of the same length with the exception of the first few sinkers associated with the needles of the instep group preceding the last instep needle to knit prior to the first course of the heel or toe, said few sinkers having shorter butts which are long enough to engage the lower casting off and flopper cams but are too short to engage the upper casting off and flopper cams.

6. In a knitting machine having main and auxiliary knitting cams and adapted to draw one or more yarns over the backs of sinkers to knit at

said auxiliary cams, a fixed sinker cam cap having on the auxiliary side a center sinker cam for drawing out sinkers which consists of two sides converging substantially to a point, a center sinker cam at the main side, two fixed casting off cams symmetrically positioned on opposite sides of said main center sinker cam and two flopper cams also symmetrically positioned on opposite sides of said center sinker cam, one of said flopper cams being below the corresponding casting off cam and the other above its corresponding casting off cam and means for automatically moving into operating position the flopper cam which is ahead of said main center sinker cam with reference to the direction of knitting.

7. In a knitting machine adapted to draw one or more yarns over the backs of sinkers, a fixed sinker cam cap having a center sinker cam for drawing out sinkers which consists of two sides converging substantially to a point, a knitting cam block having a pointed center guard cam the point of which is in the same vertical plane as the point of said center sinker cam.

8. In a knitting machine adapted to draw one or more yarns over the backs of sinkers, a fixed sinker cam cap having a center sinker cam for drawing out sinkers consisting of two sides converging substantially to a point, a side sinker cam on either side thereof for causing sinkers to move in immediately after they have been drawn out by said center sinking cam, a knitting cam block provided with a fixed sinker guard cam also having sides converging substantially to a point, said point of said center guard cam being in the same vertical plane as the point of said center sinker cam so that any needles which are lowered by said center guard cam pass under its point coincidentally with full retraction of sinkers by said center sinker cam.

9. A sinker assembly for a knitting machine which includes a rotatable sinker head and a fixed sinker cam cap, a flopper cam pivoted on the cap and means actuated by the sinker head for automatically moving the flopper cam into operating position.

10. A sinker assembly for a knitting machine which includes a rotatable sinker head and a fixed sinker cam cap having a pivoted flopper cam, and means frictionally engaging said sinker head for operating said flopper cam.

11. A sinker head for a knitting machine which includes a sinker cam cap and two pivoted, oppositely directed flopper cams, means actuated by the sinker head for moving one of said flopper cams into operating position at the beginning of knitting in one direction and for moving the other flopper cam into knitting position at the beginning of knitting in the other direction.

12. A sinker head for a knitting machine which includes a sinker cam cap and two pivoted, oppositely directed flopper cams, means actuated by the sinker head for moving one of said flopper cams into operating position at the beginning of knitting in one direction and for moving the other flopper cam into knitting position at the beginning of knitting in the other direction, each of said flopper cams being released when the other is so moved.

13. A sinker head according to claim 9 in which the sinker cam cap is provided with resilient means for moving the flopper cam out of operating position.

14. In a knitting machine of the type having a rotary needle cylinder and arranged for re-

ciprocatory knitting and which is also adapted to draw one or more yarns over the backs of sinkers, a fixed sinker cam cap having a center sinker cam for drawing out sinkers for the purpose of transferring loops from the backs to the throats of said sinkers, said sinker cam consisting of two sides converging substantially to a point and a side sinker cam on either side of said center sinker cam for causing sinkers to move in immediately after they have been drawn out by said center sinker cam.

15. In a knitting machine adapted to draw one or more yarns over the backs of sinkers, a sinker cam cap having a center sinker cam for drawing out sinkers, the two sides of said cam converging substantially to a point and a side sinker cam on either side thereof for causing sinkers to move in immediately after they have been drawn out by said center sinker cam, a cam block below said sinker cam cap, stitch cams upon said cam block including a horizontally pivoted center guard cam adapted to swing in the direction of knitting to lower needles to a level from which they can pass down the stitch cam under which they knit, said swinging guard cam being retractable and when in operating position enveloping a fixed center guard cam which when said swinging center guard cam is retracted becomes operative to lower needles but not enough to cause them to engage and pass under a knitting cam.

16. In a knitting machine adapted to draw one or more yarns over the backs of sinkers, a center cam cap having a center sinker cam for drawing out sinkers, the two sides of said cam con-

verging substantially to a point and a side sinker cam on either side thereof for causing sinkers to move in immediately after they have been drawn out by said center sinking cam, a cam block, stitch cams upon said cam block including a retractable center guard cam adapted to lower needles to a level from which they can pass down the stitch cam under which they knit, a fixed center guard cam enveloped by said retractable cam when the latter is in operating position and which becomes operative to lower needles but not enough to cause them to engage and pass under a knitting cam when said retractable cam is retracted.
